DISPENSING DEVICE

Philip A. Wooster, San Rafael, Calif.

Application March 28, 1941, Serial No. 385,659

13 Claims. (Cl. 271—2.3)

1

This invention relates to dispensing devices, and particularly to operating mechanism for devices for dispensing sheets of material from a continuous web, as for example, paper towels from a roll of toweling.

In issuing towels to patrons in a public or semi-public lavatory, the problem of waste has become an important one, and attempts have been made to prevent wasteful use of toweling, by including in the dispensing mechanism a time delay device of one sort or another for the purpose of imposing a delay after the dispensing of each towel to discourage the use of several towels by one patron where one towel will suffice adequately to perform its intended service. Such delay mechanisms have the disadvantage of often delaying the prompt delivery of towels to successive users of the device, and are therefore a source of annoyance to patrons who may attempt to dispense a towel after the preceding patron has left the dispenser but before the required time period has elapsed. Such timing mechanisms are also undesirable because they are necessarily complicated in construction, costly to manufacture, noisy, and difficult to keep accurately timed to a pre-determined interval.

It is the object of the present invention to provide a dispensing device with operating mechanism which is simple in construction and inexpensive to manufacture, and which is quiet and positive in its operation, as well as durable and designed to effect sufficient delay in the dispensing of toweling to discourage wasteful use but which will in no way interpose any delay between successive operations of the device.

Another object of this invention is to provide a mechanism that is easily and readily operable, which can dispense paper only by rotation of the operating member, and which is automatically locked against dispensing of toweling by a direct pull thereon.

It is also an object of the invention to provide a dispensing device with operating mechanism which will make possible the dispensing of any desired length of toweling, as contrasted to the usual mechanism which dispenses only towels of a predetermined length.

These and other objects are accomplished through the provision of a simple worm and gear drive for a dispensing roller which advances the towel from a continuous roll of toweling contained within the dispensing case or cabinet. The drive worm and gear are operated by a small hand crank which projects from the cabinet at a convenient and practical angle and which, due

5 to the gear ratio employed, must be rotated a plurality of times to effect dispensing of a length of toweling suitable for the usual requirement of drying the hands. Reverse operation of the crank is prevented by a simple spring clutch which disengages the handle from the worm gear upon reverse rotation of the handle, acting together with a reverse pawl locking the worm gear wheel against reverse rotation; and the 10 worm and gear drive is also effective to prevent withdrawal of toweling by pulling on the end of the towel which projects from the cabinet.

One form of the invention is more specifically shown in the accompanying drawing, and described in detail in the following specification, wherein further objects and advantages of the invention are made apparent.

In the drawing—

Fig. 1 is a front elevation of a cabinet for dispensing paper towels embodying the present invention in the operating mechanism, the cabinet being broken away in parts to disclose the interior mechanism;

Fig. 2 is a sectional view taken on line 2—2 of Fig. 1;

Fig. 3 is a sectional view taken on line 3—3 of Fig. 1; and

Fig. 4 is an enlarged detail view of a portion of the operating mechanism taken along line 30 4—4 of Fig. 3.

The dispensing cabinet shown in the drawing comprises a case to be secured against a wall in a convenient position, and a cover member arranged to conceal the contents of the case.

35 The case, as illustrated in Figs. 1 and 2, comprises a back member 10, a bottom member 11, and a pair of side walls shown at 12. The top and the front of the case are left open to facilitate the insertion of a roll of paper, and the side walls 12 are provided with outwardly extending flanges 13, which serve to lend rigidity to the structure and also serve to provide a space at both ends of the case for the reception of operating mechanism. The cover member, hinged 45 as at 14 to a member 15 which extends across the top of the case, comprises a top 16 which curves to join a front wall 17, and has a pair 50 of side walls 18 which, with the top and front portion, serve to conceal the entire case and operating mechanism, with the exception of the bottom wall thereof.

Within the case a pair of inclined shelves or ledges 19 secured one to each of the side walls 12 support a roll 20 of paper toweling by its edges in a manner to permit toweling to be

withdrawn from the roll. Journalled in and extending between the side walls 12 are a dispensing roller 21 and a pressure roller 22. The free end of the toweling is led from the roll 20 over the top of the roller 21 between the rollers 21 and 22 and to a point where it may project as indicated by the arrow 23 from an opening in the bottom of the case. Consequently, rotation of the roller 21 will effect withdrawal of toweling from the roll 20 and will eject it through the opening in the bottom of the case in the conventional manner so that it may be torn free from the continuous length to be used as a towel.

In order that the toweling may be dispensed easily and positively, and without waste thereof, the present invention provides the mechanism illustrated best in Figs. 3 and 4 for effecting rotation of the dispensing roller 21. The principal parts of the roller operating mechanism are enclosed within a small case 25, preferably secured by a flanged edge 26 to the side wall 12 by means of bolts shown at 27 or any suitable fastening means. This case 25 rotatably supports a crank 28 which extends out through the bottom of the main case of the dispenser and projects slightly forward of the front wall thereof to occupy a position easily accessible to a user, who will rotate the crank in order to dispense the length of toweling. The angle of disposition of the crank, the main axis for which is inclined forwardly and downwardly, is desirable because it enables the crank to project below the lower edge of the front portion 17 of the cover member and slotting or perforating of the cover member is therefore unnecessary, with the result that the cover is both stronger and less expensive to manufacture. This angle also insures against moisture entering the case, where it may serve to rust or otherwise deteriorate the operating mechanism, it being understood that the crank is almost invariably operated by wet hands, and in most dispensers employing an operating crank the moisture which enters the dispenser along the crank handle is sufficient to result in considerable damage over a period of time.

On the crank 28 within the case 25 is rotatably supported a worm 29. Pinned to the crank against rotation is a shouldered collar 30. The abutting ends of the collar 30 and worm 29 are of the same diameter and coiled about them is a spring 31 which serves as a uni-directional or one-way clutch, as rotation of the crank and bushing 30 in one direction tends to tighten the coils of the spring 31 which grips the shank of the worm 29 and shank of the bushing 30. On the other hand, rotation of the crank in the opposite direction tends to loosen or enlarge the coils of the spring 31, which permits it to slip over the shank of the worm 29 and/or the shank of the bushing 30. The worm meshes with a worm gear 32 which is fixed to the trunnion 33 which is the journal for one end of the dispensing roller 21. Consequently, rotation of the crank rotates the dispensing roller 21 at a greatly reduced rate of speed, the driving ratio preferably being such that a plurality of turns of the crank will be necessary to dispense a length of toweling suitable for ordinary uses. While this gear ratio may be greatly varied, depending upon the speed of operation desired, it has been found that a ratio which will effect dispensing ten or twelve inches of toweling upon some fifteen or twenty turns of the crank will effect an operation sufficiently slow to discourage wasteful use of the toweling, and at the same time

will be sufficiently rapid to prevent annoyance to the patrons using the device.

It is essential, however, to provide a worm and worm gear of such driving ratio and design that it is impossible to drive the worm by its gear and thus prevent a patron from grasping the exposed end of the toweling and pulling it out by hand. With the worm gear thus properly designed there is in effect a friction lock which prevents withdrawal of the toweling by a direct pull. Were it possible to operate the dispensing mechanism in a reverse direction, the toweling could be fed backwardly to a point where its leading end was released from between the dispensing roller 21 and pressure roller 22, and consequently subsequent operation of the crank in its proper direction would fail to dispense toweling.

To prevent this a pawl 34 is arranged to engage with the teeth of the worm gear 32 to prevent reverse rotation thereof and to insure that the crank will be freed by the clutch spring 31 in the event of attempted rotation in the wrong direction. This pawl 34 is preferably formed of a single plate shaped, as best illustrated in Fig. 4, with two ends which project through bearings 35 which are formed by perforating and pressing outwardly the side wall 12 of the main case and inwardly the side wall of the small case 25. This forms an inexpensive structure and mounting for the pawl 34 which engages the teeth of the gear by gravity, and is limited in its upward swinging movement by a stop 36 in the form of a small angular member secured to the wall 12 (see Fig. 3). The pawl is also fastened, as shown in Fig. 4, to clear a spring 37 which serves to retain the pressure roller 22 against the dispensing roller 21. The spring 37 is one of a pair mounted one at each end of the main case and extends between a fixed eye 38 and a bearing 39 which embraces a journal 40 projecting from the end of the pressure roller 22, which journal is guided between flanges 41 bent outwardly at the edges of the slot in the side wall 12. This provides a pair of floating bearings for the pressure roller 22 which are resiliently urged toward the dispensing roller 21 to facilitate removal of the roller 22 for replacement or repairs to any of its associated parts.

The slots in which its journals are guided are continued, as best illustrated in Fig. 1, in the flange 13 as shown at 42. Upon removal of the springs 37 which urge the pressure roller toward the dispensing roller, it may therefore be easily removed from its position within the case. The small case 25 must of course be first removed, and there is preferably an identical case for the opposite side to prevent unauthorized tampering with the exposed mechanism.

The toweling, after passing between the rollers, is carried toward the opening in the bottom of the case by a curved wall 43 which more or less follows the contour of the roller 21 and the lower edge of which serves as a tearing edge against which the dispensed portion of the toweling may be torn away. This wall 43 extends between the side plates of the main case and at its upper edge is provided with fingers 44 which project into grooves 45 in the pressure roller 22 to prevent any possibility of the toweling passing upwardly into the case rather than down through the discharge chute formed by the wall 43. The bottom 11 of the case is also bent upwardly under the dispensing roller 21 and is provided at its edge with fingers 46 extending into grooves 47 in the dispensing roller.

A latch to retain the cover in its closed posi-

tion is provided by a spring 48 secured to the exterior of the wall 43 and having a lower end which engages a lip on the forward bottom edge of the cover. This latch may be disengaged by a key or any suitable instrument inserted through an opening provided in the cover for that purpose. When the cover is in its closed position its lower rear corners are engaged behind and protected by clips 49 secured to the bottom of the case and projecting upwardly therefrom, and the cover may be retained in its open position by having its side walls pressed toward each other slightly so that they will engage within and be supported by clips 50 which extend upwardly from the outer edges of the flanges 13. Due to the clips 49 and 50 which serve to support and protect the cover, it may be made of considerably lighter material than is ordinarily considered necessary for such a purpose, with very much less danger of its becoming bent or otherwise damaged.

Having thus described my invention, what I claim and desire to secure by Letters Patent is:

1. Operating mechanism for a towel dispenser comprising a dispensing roller, a crank, a worm and gear drive connecting said crank and roller, and a uni-directional friction clutch between said crank and worm to prevent reverse rotation of the worm.

2. Operating mechanism for a towel dispenser comprising a dispensing roller, a crank, a worm and gear drive connecting said crank and roller, a uni-directional friction clutch between said crank and worm to prevent reverse rotation of the worm, and a pawl engaging the gear teeth to prevent reverse rotation of the gear.

3. Operating mechanism for a towel dispenser comprising a dispensing roller, a crank rotatable through at least one revolution in both directions, a worm and gear drive connecting said crank and roller, and means to prevent retraction of the toweling by operation of the crank in a reverse direction.

4. In combination with a towel dispensing cabinet, means for dispensing toweling from a supply contained therein comprising a rotatable operating crank mounted for rotation on an axis that extends downwardly and away from the cabinet.

5. Operating mechanism for a towel dispenser comprising a dispensing roller, a crank, a worm and gear drive connecting said crank and roller, means to permit reverse operation of the crank, and means to prevent retraction of the toweling by operation of the crank in a reverse direction.

6. Operating mechanism for a towel dispenser comprising a dispensing roller, a crank rotatable through at least one revolution in either direction, a worm and gear drive means connecting the crank to the roller, and a one-way clutch interposed in the drive means to disconnect the crank from the roller upon reverse turning of the crank.

7. Operating mechanism for a towel dispenser comprising a dispensing roller, a crank turnable in either direction, a worm and gear drive means

connecting the crank to the roller and arranged to require a plurality of turns of the crank to each revolution of the roller, means for preventing reverse rotation of the roller, and a one-way clutch interposed in the drive means to disconnect the crank from the roller upon reverse turning of the crank.

8. Operating mechanism for a towel dispenser comprising a dispensing roller, a crank, a worm and gear drive connecting said crank and roller, a one-way clutch interposed between the crank and the roller to free the crank on reverse turning thereof, and means for preventing reverse rotation of the roller.

9. Operating mechanism for a towel dispenser comprising a dispensing roller, a crank rotatable through at least one revolution in either direction, drive means connecting the crank and dispensing roller to rotate the roller once upon a plurality of turns of the crank, and a one-way clutch interposed in the drive means to free the crank from the roller upon reverse turning of the crank.

10. Operating mechanism for a towel dispenser comprising a dispensing roller, a crank rotatable through at least one revolution in either direction, drive means connecting the crank and dispensing roller to rotate the roller once upon a plurality of turns of the crank, a one-way clutch interposed in the drive means to free the crank from the roller upon reverse turning of the crank, and means for preventing reverse rotation of the roller.

11. Operating mechanism for a towel dispenser comprising a dispensing roller, a crank, and drive means connecting the crank and dispensing roller to rotate the roller forwardly continuously to dispense a continuous length of towel upon continuous turning of the crank, each rotation of the roller requiring a plurality of turns of the crank, said drive means providing a lock for preventing dispensing rotation of the roller except by turning the crank.

12. Operating mechanism for a towel dispenser comprising a dispensing roller, a crank, drive means connecting the crank and dispensing roller and adapted to rotate the roller forwardly through a plurality of revolutions continuously to dispense a continuous length of towel upon continuous turning of the crank, each rotation of the roller requiring a plurality of turns of the crank, said drive means preventing dispensing rotation of the roller except by turning the crank, and means for preventing reverse rotation of the roller.

13. Operating mechanism for a towel dispenser comprising a dispensing roller, a crank, a worm and gear drive connecting the crank and dispensing roller to rotate the roller forwardly continuously to dispense a continuous length of towel upon continuous turning of the crank, each rotation of the roller requiring a plurality of turns of the crank, and means for preventing reverse rotation of the roller.

PHILIP A. WOOSTER.
